[57] **ABSTRACT**

An earphone for a four channel headphone has a filling material of light weight and good sound absorbing nature closely fitted inside a unit case. Two cylindrical or conical holes are provided in the filling material in the unit case. A sound generating element is provided at the bottom of each of the holes so that the sound generating element is directed toward the free open end of the unit case and a space is maintained in front of each of the sound generating elements. The free open end of each of the holes is closed by a lid made of a gas permeable material.

FIG. 1

FIG. 2

FIG. 3

FOUR CHANNEL HEADPHONE

BACKGROUND OF THE INVENTION

1. Field of the Invention

This invention relates to the construction of an earphone for a four channel headphone to be employed in four channel stereophonic apparatus.

2. Description of the Prior Art

An earphone for a four channel headphone has a construction wherein sound generating elements such as front and rear speakers are equipped in a unit case, and for a pair of cases, each of the sound generating elements reproducing four kinds of sounds such as the front right sound, front left sound, rear right sound, and rear left sound, so that an auditory sensation as in a music hall can be obtained by a listener.

However, when two of the sound generating elements are merely encased in the limited volume of the unit case, the output sounds generated by the sound generating elements interfere with each other, whereby the resultant sound is not much different from that reproduced from a single sound generating element. Furthermore, degradation of the sound quality due to the mutual interference of the sound waves cannot be avoided.

SUMMARY OF THE INVENTION

The present invention is directed to an earphone employable in a headphone for reproducing the sound effects of the four channel stereophonic apparatus with fidelity and without the above described interference of the sounds. By preventing the interference between the front sound and the rear sound and improving the selection, the sound quality of each earphone of the dual earphone assembly the headphone is substantially improved, and the reproduction of the sounds of the four channel stereophonic apparatus has forcefulness and causes a sensation just like that at the side of the rendi-

The invention will now be described with respect to an embodiment thereof with reference made to the accompanying drawings.

BRIEF DESCRIPTION OF THE DRAWINGS

FIG. 1 is a front view of one ear side of an earphone which constitutes an embodiment of the present invention;

FIG. 2 is a sectional view taken along a centerline A-A' in FIG. 1; and

FIG. 3 is an exploded perspective view of a headphone constituting a second embodiment of the present invention.

DESCRIPTION OF PREFERRED EMBODIMENTS

In all of the figures, like parts are designated by like reference numerals and characters.

In the figures, each earphone comprises an open ended, unit case 1, provided with an ear pad 2, a lid 3 and two plugs 4 and 4', all made of a gas permeable material such as Polyform. A filler 7 made of, for instance, foamed styrol or other resin, paper, or metal, all being of light weight and of a good sound absorbing nature, is carried by the unit case 1. Through the filler 7, two holes 5 and 5' are bored. Speakers 6 and 6' are placed within the holes 5 and 5', respectively, at intermediate positions or at their bottoms thereof in a manner such

that the speakers are directed toward the open ends of the holes 5 and 5'. Suitable distances are maintained between the front surfaces of the speakers 6 and 6' and the lower surfaces of the plugs 4 and 4', respectively.

5 Furthermore, the filler 7 is placed in the unit case 1 in a sufficiently tight-fit manner to the inner surface of the case 1 that the latter will not be resonated to the sound generated from the speakers.

In order to obtain a good frequency characteristic 10 and optimum sound generating quality of the headphone, the shapes of the holes 5 and 5' may be modified so that the diameters thereof are enlarged or reduced in a conical manner. Likewise, the equipped positions of the speakers 6 and 6' may also be adjusted to 15 vary the distance between the front surface a and the bottom surface b, respectively, of the filler 7. Furthermore, the plugs 4 and 4' made of Polyform or the like may be varied in thickness or in quality, or they may be totally eliminated.

20 Each earphone according to the present invention is characterized in the above described construction, and more particularly in the construction of the holes 5 and 5'. That is, the two holes 5 and 5' are provided in the filler 7 in a spaced apart relationship, each of the speakers 6 and 6' being equipped at an intermediate position between the upper surface a and bottom b, and the holes 5 and 5' are covered, in the propagating direction of the sound wave, by lids made of Polyform or the like, whereby the propagating of the sound wave in 25 the surrounding areas can be prevented, to improve the linearity of the sound wave propagation. The vibration in air within the holes 5 and 5' can be controlled to improve the selectivity in the sound waves of different channels. Thus, the mutual interference between the sound waves belonging to different channels can be 30 substantially reduced, and the selectivity and the tone quality of the sound waves can be remarkably improved.

35 Furthermore, the two holes 5 and 5' within which speakers 6 and 6' are placed can act as horns which exaggerate the bass range of the sound waves.

40 Thus, according to the present invention, it will be apparent that a stereophonic headphone employing dual earphones of this invention four channels of superior selectivity and excellent sound reproducible nature can be obtained in two unit cases of simple construction, of light weight and at a low cost.

45 While the invention has been particularly shown and described with reference to preferred embodiments thereof, it will be understood by those skilled in the art that various changes in form and details may be made therein without departing from the spirit and scope of the invention.

50 What is claimed is:

55 1. In a two channel earphone in the form of a unit case and which is employable in a two unit case, four channel headphone assembly, the improvement wherein:

60 each unit case is open at one end,
a mass of light weight sound absorbing filling material closely fits the interior of said case,
two laterally spaced holes are provided within said material with the holes facing the open end of said case,
65 a sound generating element is provided within the bottom of each hole and faces the open end thereof,

a gas permeable plug of a diameter corresponding to said hole is inserted within the open end of each hole with each hole, being of a thickness and being spaced from a sound generating element carried therein such that the linearity of sound wave propagation is improved and mutual interference between the sound waves of the two channels is reduced.

2. The earphone as claimed in claim 1 wherein: a gas

permeable cover overlies the end of both holes carrying said plugs and is in contact with said plugs.

3. The earphone as claimed in claim 2, wherein: said holes diverge outwardly from said sound generating elements.

4. The earphone as claimed in claim 1, wherein: said holes diverge outwardly from said sound generating elements.
